ALIUS G. HATHCOCK, OF SAN FRANCISCO, CALIFORNIA.

CARBURETER.

1,125,525.

Specification of Letters Patent. Patented Jan. 19, 1915.

Application filed October 3, 1911. Serial No. 652,553.

To all whom it may concern:

Be it known that I, ALIUS G. HATHCOCK, a citizen of the United States, residing at San Francisco, in the county of San Francisco and State of California, have invented new and useful Improvements in Carbureters, of which the following is a specification.

This invention relates to improvements in carbureters, and especially in the valve mechanism thereof, the object of the invention being to provide a carbureter in which the quantities supplied of air and carbonaceous gts may be exactly proportioned to give the best result.

In the accompanying drawing, the figure is a vertical section of a carbureter constructed in accordance with my invention, the mixing chamber being shown in side elevation.

Referring to the drawing, within the casting 1 of the mixing chamber, the construction of which is immaterial to the present invention, is screwed the neck 2 of an air chamber casing 3, which has a cylindrical tubular portion or guide 4, which extends partly below and partly above the bottom of the air chamber. Upon the reduced threaded end 5 of said tubular portion 4 is screwed a nut 6 between which nut and a shoulder 7 of said tubular portion 4 is secured a float chamber casing 8, the upper edge 9 of which makes a tight joint with a circular portion of the air chamber casing 3. Gasolene is supplied to said float chamber by a nipple 11 in its casing, the conduit of which is controlled by a needle valve 12, carried by an extension 13 rigidly secured to a float 14, hinged, as shown at 15, to the inner side of the float chamber casing. Said float serves to automatically control the flow of gasolene into the float chamber, and it is suitably apertured at the center to permit the guide 4 to pass therethrough. Received within said tubular guide 4 is a tube 16, the upper end of which is screwed within the lower end of a valve tube 17 formed integral with, and depending from, a valve 18, which valve is thin and circular and has its outer circular edge 19 beveled or flaring upwardly and provided with a leather gasket 20, which seats upon the beveled edge of a seat 21 in the top of said air chamber casing.

The tube 16 has a closed bottom 22, through which extends a narrow vertical

gasolene tube 23 rigidly secured to said bottom and therefore movable with the valve tube and valve. Gasolene from the float chamber passes through a number of conduits 24 formed in the lower portion of the guide 4 and enters the bottom of said tube 23, the size of the entering passage being regulated by means of a screw 25 screwed in the bottom of said guide. Through the tube 23, immediately above the bottom of the annular chamber 16, are formed small apertures 10, one only being here shown, to afford communication between said tube 23 and annular tube 16. By the suction of the engine in the usual manner, gasolene is drawn up through said tube 23 and out through the upper end thereof, which is above the level of air holes 26 formed in the valve tube, by which air is admitted from the air chamber to the interior of said valve tube. The gasolene vapor and air are drawn up through said valve tube, and to prevent any gasolene creeping over the upper surface of said valve, said surface is made dish-shaped, or depressed toward the center, as shown at 27, to permit the gasolene to drain back into the float chamber, and there is fitted tightly within said valve tube an inner thimble 28 having a suitable number of small perforations 29 to permit of said drainage, and the upper edge of which thimble 28 extends a sufficient height above the immediately surrounding portion of the upper surface of the valve, so that said creeping cannot take place.

The thimble 28 serves an additional office of providing, by its vertical adjustment in the valve tube, for the regulation of the size of the air openings 26. It will be observed that the lower edge of said thimble is below the top of the tube 23, so that the air passing through said openings 26 has to assume an upward direction when flowing in proximity to the gasolene particles flowing upwardly in the tube 23, and therefore assists in vaporizing the same. At the same time these openings for the admission of air are direct, and not circuitous, so that the air can pass very freely to mix with the gasolene vapor.

The apertures 10 by which the tube 23 communicates with the annular tube 16, form an important feature of my invention. If these perforations did not exist, then it would be necessary for the gasolene to fill the entire tube 23 to the top thereof, before

the gasoline could arrive at a point at which air can mix with the vapor, the mixture of air facilitating the vaporization of the gasoline. This would necessitate, in addition to the suction required to draw the carbureted air to the engine, a suction sufficient to produce a column of gasoline of the height of the top of the tube 23 above the apertures 10. By forming said apertures 10, this column is broken by the admission of air to the interior of the tube 23, the air being able to flow down by the annular chamber 16, so that the carbureted mixture is drawn up through said tube 23 from the apertures 10. A further important advantage resulting from the provision of these apertures 10 is that, when the engine is at rest, gasoline passes through said apertures to the outer annular chamber 16 until the level of the gasoline in said annular chamber is the same as the level in the float chamber. Then when the engine is started again it is possible to obtain a large amount of gasoline vapor for starting from the very considerable amount of gasoline surface that is exposed to the suction of the engine, thus greatly facilitating the starting.

By the suction of the engine, not only is gasoline vapor drawn from the tube 23 and air through the holes 26, but the valve itself is lifted from its seat so that air is drawn from the air chamber between said valve and its seat. To prevent the valve being raised too high by said suction, there is provided a coiled spring 30 surrounding the valve tube, the lower end of which presses downwardly upon an outwardly extending flange 31, of said valve tube, while the upper end presses upwardly against a flange 32 extending inwardly from a tube 33 surrounding the valve tube. This tube 33 is supported, indirectly, as will hereinafter appear, by arms 34 extending obliquely downward and inward from the wall of the air chamber.

In order to accurately adjust the air inlet opening, I provide means for varying the pressure exerted by the coiled spring, which pressure resists the upward pull upon the valve caused by the suction of the engine. This I do by varying the height of the tube 33, which is formed with an external thread 35, which is screwed into an internal thread in a bevel wheel 36, which bevel gear is engaged by a bevel pinion 37 on a shaft 38 rotated in a sleeve 39 screwed through the air chamber casing, which shaft is turned by a head 40, between which head and the sleeve 39 a coiled spring 41 is compressed, thus holding the bevel pinion against the end of the sleeve. The upper side of the bevel gear is formed with a circular groove 42 which is engaged by a ring 43 carried by said arms 34, and so said ring supports said bevel gear against upward movement. A

pin 44 passed through said ring 43 and entering a vertical groove 45 in the tube 33, prevents said tube from turning. It will readily be seen that, by screwing the shaft 38, the pinion 37, and therefore also the bevel wheel 36, can be turned so that the tube 33 moves up or down, and therefore the degree of compression of said coiled spring is varied, and consequently the resistance that said spring offers to the suction of the engine is also varied, and therefore also the size of the inlet air opening, and the proportion of air to the mixture.

An important feature of my invention is the means provided for venting the float chamber. Heretofore, in carbureters, so far as I am aware, such means have been open to the objection that the vent was liable to be closed by the liquid gasoline in case of excessive tipping of the carbureter. In my invention, the casing 3 of the air chamber is formed with a partition 48 extending upwardly in such a direction as to form a narrow vertical conduit or cavity 49, the upper end of which is at a very considerable height above the float chamber. The valve 50 is located in the top of this cavity, and it will be seen that it is in such position that it is impossible for it to be submerged in gasoline by a tilting of the carbureter through an angle of 45°, that is, by any ordinary use of the carbureter.

I claim:

1. In a carbureter, the combination of an air chamber casing formed with a valve seat, a valve resting on said seat and having a tubular depending portion, the aperture of the tube extending through the valve, the air chamber casing being formed with a guide for said tubular depending portion, 100 said tubular depending portion being formed with air passages leading directly through the same and wholly below said apertures when the valve is seated, said tubular depending portion being provided at its center 105 with a narrow fluid field conduit spaced therefrom and extending to a point above the air openings in said tubular depending portions, a thimble fitting snugly within the upper part of said depending portion, the 110 upper edge of said thimble extending above the upper end of said depending portion, and the lower edge extending below the tops of the air apertures through said depending portion.

2. In a carbureter, the combination of an air chamber casing formed with a valve seat, a valve resting on said seat and having a tubular depending portion, the aperture of the tube extending through the valve, a 125 spring holding said valve to its seat, the tubular depending portion being provided with an air passage, a gasoline tube secured to and within said tubular depending portion, means for conducting gasoline into the 130

lower end of said tube, said conducting means being arranged to be enlarged or contracted by the rise or fall of the tube, and means for adjustably supporting said spring 5 from the air chamber casing, comprising a ring supported by said air chamber casing, a bevel gear wheel supported by said ring and internally threaded, an externally threaded ring screwed in said beveled wheel and having an inwardly extending flange supporting the upper end of the spring, a bevel pinion meshing with said bevel gear,

a shaft for said pinion, a bearing for said shaft, extending through said air chamber casing, and a head on the end of said shaft 15 outside the air chamber casing.

In testimony whereof I have hereunto set my hand in the presence of two subscribing witnesses.

ALIUS G. HATHCOCK.
